CLAIM

The ornamental design for a handheld smoke generator, as shown and described.

DESCRIPTION

FIG. 1 is a side view of a handheld smoke generator showing my new design;

FIG. 2 is a second side view thereof;

FIG. 3 is a bottom view thereof illustrating a second position of use for the handheld smoke generator in which a rectangular feature is open;

FIG. 4 is a top view thereof;

FIG. 5 is a front view thereof; and,

FIG. 6 is a rear view thereof.

The broken lines shown in the drawings illustrate portions of the handheld smoke generator that form no part of the claimed design.

1 Claim, 2 Drawing Sheets
